Primary Examiner—Joel Sincavage**Attorney, Agent, or Firm**—Kenneth M. Massaroni; Scott M. Garrett**[57] CLAIM**

The ornamental design for a battery pack housing for a portable computing device, as shown and described.

DESCRIPTION

FIG. 1 is a front elevational view of a battery pack housing in accordance with the instant design;

FIG. 2 is a left side elevational view thereof; and

FIG. 3 is a top plan view thereof;

FIG. 4 is a rear elevational view thereof;

FIG. 5 is a right side elevational view thereof; and,

FIG. 6 is a bottom plan view thereof.
